(57) CLAIM

The ornamental design for a paper bag with a horizontally spanning transparent window for salad ingredients, as shown and described.

DESCRIPTION

FIG. 1 is a perspective view of a paper bag with a horizontally spanning transparent window for salad ingredients showing our new design;

FIG. 2 is a front elevational view thereof;

FIG. 3 is a rear elevational view thereof; and,

FIG. 4 depicts the paper bag with a horizontally spanning transparent window for salad ingredients, with the new, original and ornamental design in a display.

The broken line showing of a shelf is included for the purpose of illustrating the bag in display and forms no part of the claimed design.

The written matter: “Italian,” “Italiennes,” “Experience the Freshness” as depicted in the drawing figures, forms no part of the claimed design. The broken lines shown in the drawings form no part of the claimed design. The stylized “Fresh Express,” and the stylized dual-leaf pattern are trademarks of Fresh Express, Inc.
